Primary Examiner — Derrick Holland*Assistant Examiner* — Lauren Calve(74) *Attorney, Agent, or Firm* — Cynthia R. Parks; Parks IP Law LLC(57) **CLAIM**

I claim the ornamental design for a blister package, as shown and described.

DESCRIPTION

FIG. 1 is a perspective view of a blister package in accordance with my design;

FIG. 2 is a left side view thereof;

FIG. 3 is a right side view thereof;

FIG. 4 is a front elevational view thereof;

FIG. 5 is a back elevational view thereof;

FIG. 6 is a top view thereof; and,

FIG. 7 is a bottom view thereof.

The broken lines shown represent unclaimed subject matter and form no part of the claimed design.
